(57) **CLAIM**

(21) Appl. No.: **29/164,760**

The ornamental design for a vehicle-windshield washer nozzle having a skull-face with illuminated eyes, as shown and described.

(22) Filed: **Jul. 31, 2002**

DESCRIPTION

(51) LOC (7) Cl. **12-06**

FIG. 1 is a front perspective view of a vehicle-windshield washer nozzle having a skull-face with illuminated eyes showing my new design;

(52) U.S. Cl. **D12/220**

FIG. 2 is a rear view thereof showing the placement of a pair of washer nozzles. The power cable for illuminating the eyes is shown in broken lines for illustrative purposes only and forms no part of the claimed design;

(58) Field of Search D12/400, 219,

FIG. 3 is a top plan view thereof;

D12/220; 239/284.1, 284.2, 600, 565, 587.4;

FIG. 4 is a bottom plan view thereof; and,

285/214-216, 194; 15/250.1; D11/55, 83,

FIG. 5 is a right side elevational view thereof, the left side being a mirror image.
